United States Patent Office

Des. 206,278
Patented Nov. 22, 1966

206,278

CONTAINER OPENER OR SIMILAR ARTICLE

Harold Charles Dowit, 11835 Sheldon St.,
Sun Valley, Calif. 94087

Filed June 14, 1965, Ser. No. 85,723

Term of patent 14 years

(Cl. D44—29)

I claim:

The ornamental design for a container opener or similar article, as shown.
